(57) **CLAIM**

The ornamental design for an wrapped pet treat, as shown and described.

DESCRIPTION

FIG. 1 is a front, top and left side perspective view of a wrapped pet treat according to the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The break lines shown in the middle portion of the wrapped pet treat in FIGS. 1–5 indicate that the appearance of any portion of the article between the break lines forms no part of the claimed design.

The stippled shading and non-stippled shading shown in FIGS. 1–7 represent a contrasting appearance.
